No. 729,553.

PATENTED JUNE 2, 1903

W. A. DEMMON.

TRANSFORMATION SCENE.

APPLICATION FILED JAN. 8, 1901.

NO MODEL.

UNITED STATES PATENT OFFICE.

WILLIAM A. DEMMON, OF NEW YORK, N. Y., ASSIGNOR OF ONE-HALF TO
C. WIN PERKINS, OF HARTFORD, CONNECTICUT.

TRANSFORMATION SCENE.

SPECIFICATION forming part of Letters Patent No. 729,553, dated June 2, 1903.

Application filed January 8, 1901. Serial No. 42,508. (No model.)

To all whom it may concern:

Be it known that I, WILLIAM A. DEMMON, a citizen of the United States, residing in the city of New York, State of New York, have invented certain new and useful Improvements in Transformation Scenes, of which the following is a specification, reference being had therein to the accompanying drawings.

My invention relates to the application of the principle covered by my former patent, No. 537,441, to use as a toy and advertising novelty, but in construction and manner of operating essentially differing and entirely new and original.

It consists of a novel arrangement and combination of parts whereby two pictures may be brought into view alternately in such manner that while any certain portion of the first picture is disappearing the same portion of the second is appearing and taking the place just vacated by the one disappearing.

In the drawings which illustrate my invention, Figure 1 represents the first picture in view, while in Fig. 4 is shown the top half of the second picture where the top half of the first has disappeared and the bottom half of the first is still in view. Figs. 2 and 3 are vertical sectional views taken on line X of A. Fig. 5 shows the various parts separately, drawn on a reduced scale.

In the construction I employ a frame I, of cardboard, sheet metal, wood, or other suitable material, in which is a rectangular opening large enough to show the picture and to which both ends of a strip of cloth or other flexible material on which are depicted the pictures is securely attached at 2 3. 4 is another piece of cardboard, sheet metal, wood, or other suitable material, in which and extending almost across it is the narrow slit 5. It also has the long handle-piece 4^a, which extends slightly below the frame I and is used to operate the moving parts, as hereinafter described.

6 is a piece of cardboard, sheet metal, wood, or other suitable material which slides up and down on the back of 4 when in operation and is designed to take up the slack in the cloth as it is fed through the slit 5 by moving 4 up and down. The cloth is securely attached to 6.

7 is a narrow strip fastened at its ends to

4, hiding from view the slit 5 and the cloth where it passes through slit.

In Fig. 2 the cloth is shown fastened to the frame I at point 2. It passes down and through slit 5, then up over the top of 6, then down around the bottom of 6 and up through slits 5, then down to point 3, where it is again fastened to I.

Fig. 3 is the same sectional view shown in 2, except that all the working parts have moved down to position they occupy when showing the second picture.

In Figs. 2, 3, 4 the parts are shown slightly separated; but in operation they lie close together and are held in position by an outer envelop or box. (Not shown.) Fig. 4 is a front view with right-hand side removed on line X, Fig. 1, showing handle 4^a and slit 5, with strip 7 and piece 6 moved one-half way down and position occupied when showing half of each picture.

The entire machine is to be cased in an envelop-box or other suitable covering, having a rectangular opening to correspond with the opening in frame I. By this arrangement, as shown in Fig. 2, the first picture is in full view through the opening in I, and by pulling down the handle 4^a the first picture disappears through the slit 5 and the upper edge of slit pulling against the fold in the upper position of cloth causes 6 to be pushed down, which, being attached to the cloth, in descending pulls the lower portion with it, thus drawing the lower picture back out of view through slit 5, forming a fold in the lower portion of the cloth similar to that just being fed through the slit from behind and above, bringing the second picture into view as the first disappears.

While I have shown this to be operated by the handle 4^a, I do not wish to confine myself to this mode of operation, as handle 4^a may be dispensed with and a string, wire, or other suitable material be attached to either 4 or 6, by which they could be pulled down and up, or handle 4^a may be made a part of and attached to 6.

Having thus described my invention, what I claim, and desire to secure by Letters Patent, is—

1. In a device of the character described, the combination of a movable portion having

a central slot through which the ribbon adapted to bear the pictures passes and a strip extending over the said slot secured to the plate at its ends and raised between the said ends.

5. 2. In a device of the character described, the combination with a suitable wrapper or casing, of a fixed plate having an opening therein, a strip or ribbon of greater length than the said fixed portion or plate, a movable plate, a slot in said movable plate through 10 which the intermediate portions of the strip

are passed, pictorial representations on the said strip adapted to be alternately presented before the opening in the fixed plate by the movement of the said sliding plate; the ends 15 of said strips being secured near the ends of the fixed plate.

WILLIAM A. DEMMON.
